CURTAIN AND DRAPERY SUPPORT

Alex Ziolkowski, Chicago, Ill.

Application June 22, 1938, Serial No. 215,148

1 Claim. (Cl. 156—22)

This invention relates to supports or racks for curtains and draperies, and particularly to supports adapted to be fastened to walls and window or door frames.

The main object of the invention is to produce a support for curtains and the like, comprising a pair of fixtures to be fastened in spaced relation to a wall or frame, a pair of cooperating supporting members, one of which is removably mounted in each fixture, the supporting members of said pair being separately adjustable longitudinally, and a locking device for connecting the proximate ends of the supporting members.

A further object is to provide means in the fixtures for pivotally connecting each of the supporting members to the fixture and for limiting the pivotal movement of said supporting members.

Another object is to provide a support for curtains and the like, in which the curtain supporting bars may be connected detachably to extend continuously from one attaching fixture to the other or may be spaced apart between their proximate ends, either midway of the attaching fixtures or at one side or the other of said median point. The advantages of this and other features of construction will be explained in the following specification.

The invention may be embodied in single or multiple type supports, but in the drawings I have shown the double type, suitable for supporting glass curtains and draperies.

In the drawings:

Fig. 1 is a front elevation of a support embodying my invention.

Fig. 2 is a plan view of same.

Fig. 3 is a horizontal sectional view, on an enlarged scale, through part of the support, on the line 3—3 of Fig. 1.

Fig. 4 is a perspective view of one of the locking or connecting devices used in the invention.

Fig. 5 is a front elevation showing the forward one of the two supports adjusted to separate the bars of the pair constituting said support.

Fig. 6 is a plan view of the support of Fig. 5, with one side of the forward supporting bar pivotally swung to another position.

Fig. 7 is a perspective view of the free end of one of the forwardly located bars of Figs. 5 and 6.

Fig. 8 is a plan view of a modified form of the support.

In that embodiment of the invention shown in the drawings, identical fixtures 10 each comprise

a flat plate 11 having flanges 12 extending horizontally from its upper and lower edges. For the double type support, the fixtures 10 are provided with flanges 12 of sufficient width to accommodate two pivot pins 13, but obviously the flanges 12 may be made to accommodate one or more pivot pins 13. On each of the pins 13 there is pivotally mounted between the flanges 12, 12 of the fixture 10, a short arm 14 consisting of a piece of metal curved at 15 and bent to form an end portion 16 substantially at right angles to the adjacent portion. The metal of the arm 14 is also bent longitudinally along each side to form retaining members 17 which are spaced from and parallel to the flat part of the arm 14, and to form means 18 for mounting the arm 14 on a pivot pin 13. Normally the end portion 16 of the arm bears against the plate 11 of the fixture 10, whereby the movement of the arm in one direction is limited.

The fixtures are adapted to be fixedly secured to a wall or frame by nailing or screwing the apertured plates 11 thereto. Said fixtures are used in pairs and may be used interchangeably as either right or left members, and spaced apart as required.

The arms 14 of a pair of fixtures cooperate to support bars or rods which may extend from one fixture to the other continuously or have their free ends spaced apart. In Figs. 1, 2 and 3, the curtain supporting bars extend across the window or door, from one fixture 10 to another. Said bars are identical with the exception that the ends of the outermost bar (that is, the one farthest removed from the window or wall), engaging the fixture arms 14, are longer than the corresponding part of the inner bar.

The curtain supporting bar comprises two members, each consisting of a bent bar 19 having fixed at one end a flat loop 20, and a straight bar 21 having fixed at one end a flat loop 22. The bar 19 extends through the loop 22 on the bar 21 and the bar 21 extends through the loop 20 on the bar 19, whereby said bars are slidable on each other and their length is adjustable. The inclined portion 23 of each bar 19 is adapted to be inserted in an arm 14, between the arm body and retaining member 17, to be frictionally held therein. The free ends of the bars 21, 21, adjusted to meet about midway between the fixtures 10, are detachably connected by a locking device 24 shown in perspective in Fig. 4. It comprises a flat plate having flanges 25, 25 on its edges and retaining tongues 26, 26 indented at 27, 27. The locking device 24 serves as a con-

nection for the proximate free ends of the bars 21, 21, and the projections 27 engage apertures 28, 28, in said bars 21, 21, as shown in Fig. 3, to hold the members together frictionally.

- 5 The curtain supporting bars consisting of the members 19 to 24, inclusive, are identical, as explained, excepting as to the length of the portions 23 and 23' of the respective inner and outer bars.
- 10 In Figs. 5 and 6, the inner curtain supporting bar is identical with the corresponding bar of Figs. 1 to 3, but the outer of the curtain supporting bars has been modified by removing the locking device 24 and shortening the length of the 15 members by sliding the bars 21 toward their respective supporting fixtures. A spear or ornament 29 having a retaining member 30, as shown in Fig. 7, may be slipped over the free ends of the bars 21, 21, as shown in Figs. 5 and 6. When 20 thus altered the outer curtain supporting members may be swung about the pivot point 13 as shown at the right hand side of Fig. 6.

The structure shown in Fig. 8 is similar to that described excepting that the curtain supporting 25 bars are curved instead of straight. The parts corresponding to members 19 to 22 inclusive have been designated 31 to 34, respectively, and the curved locking devices 35.

One of the advantages of my construction is the 30 fact that the curtain supporting bars may be used as desired, to extend continuously across the space between the fixtures or separated to provide side supports, and the latter are separately adjustable as to length. Thus it is unnecessary to 35 remove either the curtains or supporting bars when it is desired to wash windows. The curtain, if one piece, may be moved to one side of the locking device 24 or 35, the end of one bar 21 or 33 removed from the locking device, and the sup- 40 porting member carrying the curtain may be

swung about the pivot 13 and out of the way. There is enough spring or play in the bars to permit disengagement of the whole bar from one of the arms 14, allowing the bar to swing at its opposite end, to carry the curtain away from the 5 window. If the curtain is a two panel curtain, it is only necessary to disengage the locking device 24 or 35 from one of the bars 21 or 33 and to swing both halves of the supporting means and curtains out of the way.

The adjusting means permits independent and equal or unequal extension and contraction of the bar portions at opposite sides of the locking devices 24 or 35.

The shape of the part 16 of the arm 14, bearing 15 on the fixture plate 11, prevents unintended movement of the arm 14 toward the wall or window.

Changes may be made in details of construction without departing from the scope of my invention.

I claim:

A curtain rod comprising two identical members each consisting of a pair of bars telescopically connected together, a locking device detachably engaging the proximate ends of said identical members when they are in aligned, end abutting relationship, the opposite outer free ends of said identical members being adapted for insertion, by movement of said bars longitudinally of 30 each other, in pivotally mounted supports, each of said members being independently swingable with its pivoted support when said locking means is disengaged, and said rod as a whole, with the locking device in place, being withdrawable from 35 one of said supports by telescoping one of said bars relatively to another, whereby said rod as a whole is swingable with one of said pivoted supports.
